UNITED STATES PATENT OFFICE

JOSEPH KOENIG, OF MANITOWOC, WISCONSIN; REMUS KOENIG AND RUBY K. ELLIS
ADMINISTRATORS OF SAID JOSEPH KOENIG, DECEASED

PROPELLER

Application filed March 25, 1929. Serial No. 349,626.

This invention relates to new and useful improvements in propellers.

One of the objects of my invention is the provision of a propeller which can be used equally as well either in water or for air and is so constructed that during the operation of the propeller the centrifugal force of the same will expel the air or water at substantially right angles to the intake of the air or water thereby producing a partial vacuum between the inner wall of the propeller and the volume of water or air so as to create a forward suction to impart movement to the object to which the propeller is attached.

Another object of my invention is the provision of a propeller of the above type which while not reversible is so constructed that with very little change in the device it can be used either in water or air and operate equally as efficient in one as in the other.

Another object of the invention is the provision of a propeller which includes in its construction a backing disc with a central shaft extending therethrough and the propeller blades carried by the shaft so that the action of the air or water is such that the fluid will enter the blades at the front and through centrifugal force be expelled over the peripheral edge of the blade before it reaches the disc, thus creating a vacuum between the disc and the body of the blades so that the fluid will not come in contact with the body being propelled and reduced to a minimum the action of the air or water on the body.

With the above and other objects in view, the invention consists in the novel features of construction, the combination and arrangement of parts hereinafter more fully set forth, pointed out in the claim and shown in the accompanying drawings wherein:

Figure 1 is a longitudinal section view through my improved propeller with parts in elevation;

Figure 2 is a transverse section on the line 2—2 of Figure 1; and

Figure 3 is a detail section on the line 3—3 of Figure 2.

Referring more particularly to the drawings, it will be noted that the improved pro-

peller is mounted upon shaft 1, the outer end of which is provided with a circular head 2 bolted or otherwise secured to a disc 3. Longitudinally aligned with the shaft 1 is a tubular part 4, the inner end of which is formed with an annular flange 5 adapted to be disposed between the head 2 and the disc 3 and secured in position by means of the bolts 6 which are used for connecting the disc 3 to the head.

In the construction of the propeller, the blades are preferably formed in pairs, not only for the convenience of providing propellers at a very low cost, but for the purpose of reducing to a minimum the fastening members for securing the blades to the tubular shaft 4.

The blades are formed in pairs as shown in Figure 2, the blades 7 and 7' being integrally connected by means of the transverse portion 8 so as to form substantially U-shaped members with the outer edges of each side portion which constitutes the blade 7 and 7', slightly curved as shown at 9. The inner ends of each of the blade members are provided with perforated lugs 10 which may be bolted or otherwise secured to the disc 3 in order to retain the blades in their proper relative position with respect to the tubular shaft 4.

The blades 7 and 7' adjacent their outer ends are connected by means of a band 11 which extends entirely around the propeller and is bolted or riveted to the curved portion 9 on all of the blade members, thus the blade members are rigidly secured and retained in spaced relation with respect to each other as is clearly illustrated in Figure 2. This band 11 may be of any suitable width but is preferably narrow in order to offer as little resistance as possible when the propeller is travelling through fluid.

When using the propeller on an airplane or where the propeller is to contact with air only, the outer ends of the blades 7 and 7' may be left comparatively straight, but where the propeller is used in water or fluid heavier than air, it is preferred to have them slightly curved as shown at 12 so that the water will not be impeded in its progress

when entering between the blades and not enter the blades with considerable shock or force and the action of the propeller, will have a tendency to cause the curved portion 5 to cut a forward path in the water as the water enters in between the propeller blades. The centrifugal force of the propeller will cause the water to be directed outwardly over the curved longitudinal edges of the blades 10 before the water reaches the disc 3, thus creating a vacuum between the inner end of the propeller and the body to which the propeller is attached so that the water will offer the least possible resistance to the body passing 15 therethrough as the vacuum created by the lateral discharge of the fluid from the blades will have a tendency to drive the fluid from the body. This action also takes place when using the propeller as an air propeller. 20 In constructing the propeller either for use in water or as an air propeller, it will be readily apparent that the axis as well as the blades will necessarily have to be longer when constructing the device for an air propeller as the action of the air is much faster 25 than the heavier water therefore, it will be necessary to extend the length of the blades so that the centrifugal force will have a tendency to discharge the air laterally from 30 the blades before it reaches the disc 3. The propeller to be used in water can be considerably shorter as the slow action of the water will permit the propeller to discharge the same laterally from the blades before it reaches the disc 3. 35

In order to close the outer end of the tubular shaft part 4, I provide a plug 13 having a conical cap portion 14 which will have a tendency to direct the fluid contacting therewith, between the blades 7 and 7'. This conical part 14 will offer very little resistance to the fluid through which the propeller is passing and will materially assist in directing the fluid outwardly between the propeller blades. 40 It will be apparent from the foregoing that I have provided a simple and inexpensive propeller wherein the construction of the blades is such as to permit the blades to be readily manufactured at a very low cost, 45 and even though the blades in the present instance may be shown as constructed in pairs, it will be apparent that the blades can be formed with each blade connected to the shaft part 4, or more than two blades may be fastened on the center by the same set of bolts or rivets. 50

It will also be apparent that with very little change, the device can be used equally as well in water or as an air propeller. 55 The disc 3 may be on the other end of the shaft which would allow the propeller to be placed at the back end of the ship and push the ship forward. 60

I claim—
65 In a propeller of the class described, a

central shaft, a plurality of blades mounted upon the shaft and secured thereto, said blades radiating from the shaft with their outer ends all curved in the same general direction, a band encircling the blades at their outer ends, and having connection with each blade adjacent the curved end, a disc mounted upon the shaft at the inner end of the blades and connected to each blade for closing the inner end of the propeller. 70

In testimony that I claim the foregoing I have hereunto set my hand at Miami, in the county of Dade and State of Florida. 75
